UNITED STATES PATENT OFFICE.

JOHN G. SEEING, OF RIPPON, WISCONSIN, ASSIGNEE TO BARLOW & SEEING MFG. CO., A CORPORATION OF WISCONSIN.

CONTROL MECHANISM FOR WASH WRINGERS.

Application filed September 23, 1922. Serial No. 590,138.

To all whom it may concern:

Be it known that I, JOHN G. SEEING, a citizen of the United States, and a resident of the city of Ripon, in the county of Fond du Lac and State of Wisconsin, have invented certain new and useful Improvements in a Control Mechanism for Wash Wringers; and I do hereby declare that the following is a full, clear, and exact description of the same, reference being had to the accompanying drawings, and to the numerals of reference marked thereon, which form a part of this specification.

It is an object of this invention to provide an improved mechanism for driving the wringer attached to a washing machine.

It is a further object of this invention to provide an improved way of supporting the wringer in any of a number of positions in relation to the machine.

It is a further object of this invention to provide a housing for the mechanism driving the wringer which shall be made of few parts and readily and easily assembled.

It is a further object of this invention to provide a direction changing clutch of a form that shall enable the handle controlling the same to be so positioned that it is easily accessible.

Other and further important objects of this invention will be apparent from the disclosures in the accompanying drawings and following specification.

The invention (in a preferred form) is illustrated in the drawings and hereinafter more fully described.

On the drawings:

Figure 1 is a view of one corner of the washing machine and a wringer support attached thereto, certain parts being shown in section.

Figure 2 is a view of the wringer and control mechanism taken at right angles to Figure 1.

Figure 3 is a section upon the line 3—3 of Figure 2.

Figure 4 is a section upon the line 4—4 of Figure 3.

Figure 5 is a section upon the line 5—5 of Figure 3.

Figure 6 is a section upon the line 6—6 of Figure 5.

Figure 7 is a top plan view of the lower part of the housing, certain parts being shown in section.

As shown on the drawings:

The washing machine cabinet 10 is provided with a bracket 11 which supports the vertical cylindrical housing 12 for enclosing a shaft 13 at the lower end of which is mounted a bevel gear 14. This meshes with a bevel gear 15 on a horizontal shaft projecting through the wall of the washing machine cabinet. The two bevel gears are enclosed within a triangular housing which is integral with the bracket 11.

The upper end of the cylindrical housing 12 is provided with a horizontal table 17 the edges of which are flanged as shown at 18 to provide a circular saucer-shaped seat for receiving the circular foot 19 of a rotatable casting 20 which has a column extending from the foot 19 to the body of the casting. This column includes a cylindrical part 21 and ribs or flanges 22.

The column also has a projecting part similar to the ribs but of greater cross section as shown at 23. This part is made hollow, and the bore thereof as shown at 24 is cylindrical in order to house a spring 25 and a plunger 26. A slot 27 is provided in the outer side of the projection 23 to accommodate the stem 28 of an operating pin having a head 29. The lower end of the plunger 26 has a projecting end 30 adapted to enter any of a number of holes 31 provided in the table 17 and forming a circular series surrounding the shaft 13. In the form illustrated only two of these holes are shown, but any desired number may be provided to make it possible to secure the wringer in any desired number of positions.

Above the column 21, the casting 20 is provided with a hemispherical bowl 32 for housing the manually controlled motion reversing clutch for the wringer. At one side this bowl is provided with a projection 33 which forms the lower half of a bearing for the shaft 42 which drives the wringer. The lower half of a second bearing for this shaft is provided on the opposite side of the bowl at 34. Beyond the half-bearing 34 the casing 20 is provided with a larger half-bearing 35, to receive a hollow sleeve 36 which is provided with a square socket 105 for the reception of the square end of the wringer shaft 37.

The housing of the clutch is completed by a supplemental casing 38 which has a hemispherical cap 39 to cover the upper part 110

of the clutch. At one side the cap 39 is provided with a projection 40 to cooperate with the projection 33 and make a bearing for one end of the shaft 42. At the other side of the cap 39, the casting 38 is provided with a semi-cylindrical part 43 which affords a half bearing to cooperate with the half bearing 34 for the shaft 42 and a larger half bearing to cooperate with the half bearing 35 for the sleeve 36. Bolts 44 secure the two halves of the housing together in the usual way.

The vertical tube afforded by the columnar parts 12 and 21 is lined throughout its length with a tubular lining 50 which is provided at suitable intervals with bushings 51 to guide and support the shaft 13. Pinned to the upper end of the shaft 13 and bearing against the upper end of the lining 50 is a bevel gear 52, which meshes with either one of two bevel-gears 53 and 54. These gears are pinned to the shaft 42 and they and the shaft move together both in rotat-ing and in lengthwise travel.

To provide for this lengthwise travel, an eccentric disk 57 is positioned between the gears 53 and 54, and bears against the inner faces of them. This is called an eccentric disk because it is eccentrically connected to a short shaft 60. The shaft 60 is guided and supported in a boss 61 formed in the upper part of the hemisphere 39. The upper edge of this boss is provided with V-shaped notches 62, preferably three in number, although more may be used. Pinned to the upper end of the shaft 60 is a handle 63. The hub of this handle is provided with a V-shaped projection 64 which is adapted to fit in any one of the notches 62. The shaft 60 is yieldingly held in position by the spring 65. One end of this spring bears against the under face of the boss 61 and the other end of the spring bears against the disk 57.

In the operation of the device:

Moving the handle 63 will cause the projection 64 to slide out of the notch 62, moving the shaft 60 a short distance longitudinally and thus compressing the spring 65. When the handle 63 has been rotated far enough so that the projection is opposite the next notch 62 the spring 65 will expand bringing the shaft 60 and disk 57 to the same height that they originally occupied and the projection into the new notch. This introduces a certain resistance to the motion of the handle 63 and the operator is thus enabled to readily select the correct position of this handle.

In one of these positions the disk 57 will have its larger side toward the projections 33 and 40. At a position 90° removed from this the disk will extend equally on the two sides of the shaft 60 toward the projection 33 and toward the bearing 34. In the posi-

tion 180° removed from the first described position the larger side of the disk will be toward the bearing 34. Since the gears 53 and 54 contact with the disk 57, they will move from the position illustrated in Fig. 5 which corresponds to the first described position of the handle to a position in which neither the gear 53 nor the gear 54 meshes with the gear 52 which corresponds to the second described position of the handle. When the handle 63 is moved further the gears 53 and 54 will come to a position which is the opposite limit of their travel and in which the gear 54 will mesh with the gear 52 and the gear 53 will be out of mesh. This corresponds to the last described position of the handle. Since the shaft 13 and the gear 52 are continually driven in the same direc-tion the shifting of the shaft 42 to bring one or the other of the gears thereon into mesh with the gear 52 will reverse the wringer as is well known in the art. When this handle 63 is in an intermediate position so that neither of the gears 53 and 54 mesh with the gear 52 the wringer will not be driven. Thus rotation of the wringer is completely controlled by position of the handle 63. The shaft 42 moves longitudinally as the gears 53 and 54 shift and the sleeve 36 moves with it. In the illustrated position the end of the sleeve is substantially flush with the face of the castings 20 and 38 while the end of the shaft 37 does not reach to the bottom of the socket. In the opposite position the sleeve 36 is pro-truded and the end of shaft 42 is very close to the end of the shaft 37.

The position of the wringer may be altered by rotating the housing made up of the two castings 20 and 38 about the shaft 13 as an axis. To do this the head 29 is first raised so that the end 30 of the plunger 26 is no longer seated in a hole 31. The castings are then free to rotate, carrying the wringer with them. When the rotation has proceeded so far that the position of the wringer corresponds with the next hole 31, the spring 25 causes the end 30 to snap into this hole and the wringer is locked in the new position. Two holes 31 are provided, one corresponding to a position where the clothes are wrung either into or out of the tub, depending upon the position of the handle 63, and the other corresponding to a position in which the clothes are wrung from one receptacle to another, both outside the tub. Obviously other positions may be used if desired by increasing the number of holes 31.

I am aware that numerous details of construction may be varied through a wide range without departing from the principles of my invention, and I therefore do not pur-pose limiting the patent granted otherwise than necessitated by the prior art.

I claim as my invention:

1. In a device of the class described, a hollow spherical casing having a horizontal bearing extension provided with an enlarged bore, a slideable bearing sleeve in said enlarged bore, one portion of said sleeve having a circular axial bore, and another portion of said sleeve having a polygonal bore, a slideable shaft supported in said casing and extending into said sleeve, means for securing said shaft and sleeve for conjoint rotation, a driven shaft extending into said polygonal bore, means for driving said first mentioned shaft, and means for shifting said first mentioned shaft.

2. In a device of the class described, a hollow spherical casing having a horizontal

bearing extension provided with an enlarged bore, a bearing sleeve slideable in said enlarged bore, a shaft slideably supported in said casing and extending into said sleeve, means for securing said shaft and sleeve for conjoint rotation, a pair of gears secured upon said shaft, means for engaging and shifting said shaft and gears and driving mechanism for rotating said gears and shaft.

In testimony whereof I have hereunto subscribed my name in the presence of two subscribing witnesses.

JOHN G. SEELIG.
